United States Patent Office.

REUEL BLACKWOOD, OF PHILADELPHIA, PENNSYLVANIA.

Letters Patent No. 85,558, dated January 5, 1869; antedated December 30, 1868.

IMPROVED MACHINE FOR PIERCING STITCH-HOLES.

The Schedule referred to in these Letters Patent and making part of the same.

To all whom it may concern:

Be it known that I, REUEL BLACKWOOD, of the city of Philadelphia, in the State of Pennsylvania, have invented a new and useful Machine for Piercing Stitch-Holes in thick leather; and I do hereby declare that the following is a full, clear, and exact description of the construction and operation of the same, reference being had to the accompanying drawings, making a part of this specification, in which—

Figure 1 is a perspective view of the said machine, and

Figure 2, a side elevation of the same, partly in section, like letters of reference indicating the same parts when in both figures.

In stitching together longitudinally, two or more long strips of thick leather, as required in harness-traces, and other similar manufactures of leather, the piercing of the stitch-holes has heretofore been done by hand, which mode of operation is not only slow and laborious, but it is difficult, even to the most skilful workman, to thus produce a true or regular line of uniform stitches on both sides of the article—a result much desired for the best quality of harness; and

The object of my invention is to afford a machine, or combination of mechanical devices, to be attached to a saddler's sewing-bench, whereby, when the article to be stitched is appropriately held in the clamp of the bench, a regular line of stitch-holes, at uniform distances apart on both sides of the article, can be readily produced in the most rapid and perfect manner, leaving nothing to be done afterward by the workman, except to pass the threads through the holes, and draw them tight, to produce the most perfectly-even and uniform stitches on both sides of the said article, as required.

My invention consists, substantially as hereinafter described, in the application to a saddler's sewing-bench or other suitable clamp, of a combination of mechanical devices, whereby a piercing-awl attached thereto can be alternately forced through and withdrawn from the article to be stitched, and the said awl caused to be moved periodically along beside the said article, the space of a required stitch, by means of a treadle, or its equivalent, attached to the bench or floor, and operated by the workman.

Referring to the drawings—

A B is a metal frame, having its two parallel opposite inner sides grooved longitudinally, and having, also, a screwed shaft, C, with its journalled ends secured in the middle of the ends of the said frame A B, so that it can be rotated in position, one of the journals of the said shaft projecting through the further end of the said frame A B, and having thereon a loose cylinder or broad pulley, c', with a pawl, c", attached at one end, and also a ratchet-toothed flange, c'', or wheel, fixed on the shaft's journal, the said cylinder, pawl, and ratchet-wheel being so arranged that the pawl c" will rest successively in the teeth of the ratchet-

wheel c'', in such a manner that when the cylinder c' is rotated in one direction, it will rotate the screw-shaft C, and when rotated in the opposite direction, it will slip loosely around on the journal, the said shaft being applied so as to have friction enough in its bearings to prevent it from being rotated in the latter case. (See fig. 1.)

This frame A B is fixed permanently in a horizontal position, across one side of the clamp of a saddler's bench, as indicated by the faint lines in the same figure.

Supported by the two parallel grooves in the frame A B, is an upright piece, D, which is made so that it can be readily slid along by hand, backward and forward, in its upright position in the frame A B, it being undercut at d', so as to pass clear of the screwed shaft C.

Attached to the rear side of this upright, D, there is a small latch or drop-lever, d'', the inner edge of which fits between any two of the threads of the screwed shaft C, and thus connects the upright, D, with the said shaft, and causes it to be moved along on the frame A B, when the said shaft is being rotated. (See fig. 1.)

Adjustably attached to the upper end of the upright, D, there is a hollow cylindrical piece, E, arranged horizontally, at right angles to the frame A B, and having a slot, e', along in the near side.

Within this hollow piece E, a solid piece, e', fits, so that it can be slid accurately backward and forward in longitudinal directions therein. In the end of e' which is next to the clamp of the sewing-bench, (to which the machine may have been applied,) the piercing-awl e'' is firmly and detachably fixed, whilst the other end of e' extends about two inches, more or less, beyond the hollow piece E, and is surrounded by a spiral spring, e', one end of which spring abuts against the end of the hollow piece E, and the other against the flange or head on the outer end of e', and thus the said spring holds the awl-end of e' about flush with that end of E, and at the same time allows the piercing-awl e'' to be pressed forward, when so required, as will herein be described.

Attached also to the upright, D, there is a strong lever, F, of the first class, which oscillates on a fulcrum-pin, f', in the upright, D. The upper end of this lever F extends up alongside of the hollow cylinder E, and has a slot, f'', which receives part of a stud, e', which is fixed in e', and projects horizontally out through the slot e'' in the hollow cylinder E. The lower or power-end of lever F extends downward about an inch, more or less, below the lower end of the upright, D, and has an offset, f''', thereat.

To the lower end of the upright, D, there is pivoted a strong arm, G, which has an upright spring-latch, g', (see fig. 2,) which will slide over and catch behind an inclined projection, f', which is fixed on that side of the lever F, for the purpose, when the said arm G is raised upward sufficiently, and which will, when the said arm is being drawn downward, carry the lower end of

the lever F outward a certain distance, and then let it go back again, as will herein be described.

The outer end of arm G is intended to be connected, by means of a stiff rod (not shown) to any suitable treadle, which is to be attached to the supports of the sewing-bench or floor, so as to be accessible by the foot of the operator sitting on the bench, or as indicated by the faint lines in the drawings.

The cylinder e' is intended to be connected to the same treadle, and at a point nearer to its fulerum, by means of a cord, which, passing upward therefrom, and three or four times tightly around the said cylinder e', is to be then passed downward and secured to a spiral or other spring, strong and elastic enough to quickly lift the treadle, and thus elevate the arm G to the position shown in the drawings, when the foot of the workman is removed therefrom, and also at the same time cause the shaft C to be rotated in a screwing direction, or so as to cause the upright, D, with its appendages, to be moved along on the frame A B the length of the intended stitch. The length of the stitch is to be regulated by attaching the cord which rotates the cylinder e' nearer to or further from the fulerum of the treadle, as a shorter or longer stitch may require.

Operation.

The workman, seated upon a sewing-bench to which this machine is attached, as described, and securing in a horizontal position, between the clamps, the trace or other article to be stitched, the height of the awl e'', and the intended length of the stitch being provided for by adjusting the parts of the machine accordingly, he lifts the latch d'', and then pulls the upright, D, toward him, to the full limit of the frame A B, and then readjusts the latch into connection with the screw C. He then places his foot upon the elevated treadle, and, pressing it downward, draws down the arm G from the elevated position shown in the drawings, to the depressed position shown by the dotted lines, thus

having caused the awl e'' to be forced through the thick leather in the clamp by the pressure of his foot, and the said awl to be suddenly withdrawn therefrom by the reaction of the spring e'. He now lifts his foot off the treadle, and the reaction of the spring, which is attached to the cord leading from the treadle, and around the cylinder e' to the said spring, as described, causes the shaft C to rotate in a forward or screwing direction, and consequently to move forward the awl e'' the space of a stitch, and so on, until the upright has reached the further end of the frame A B. He now sews in the stitches, moves the stitched article along in the clamp, to a new position, and recommences the piercing of stitch-holes.

It will be readily seen that, by means of this machine, the stitching of harness-traces and similar articles of thick leather can be done with the greatest facility, ease, and rapidity, and that, on both sides of the article, the line of stitches will be perfectly regular, and the stitches of uniform lengths and positions.

Having thus fully described my invention,

What I claim as new, and desire to secure by Letters Patent, is—

The application, to a saddler's sewing-bench, or other suitable leather-holding clamp, of a machine consisting of the following elements, viz, a fixed frame, A B, having a screwed shaft, C, cylinder e', pawl e'', and ratchet-flange e'' attached, in combination with a sliding upright, D, provided with a hollow piece, E, sliding piece e', piercing-awl e'', spring e', latch d'', lever F, and arm G, the said machine being connected with any suitable actuating-treadle, cords, and spring, or their equivalents, and operating the piercing-awl e'', substantially in the manner and for the purpose described.

REUEL BLACKWOOD.
